UNITED STATES PATENT OFFICE.

CHARLES W. UNDERWOOD, OF CROWLEY, LOUISIANA, ASSIGNOR OF ONE-HALF TO
WILLIAM M. EGAN, OF CROWLEY, LOUISIANA.

MICROPHONE.

1,136,449.

Specification of Letters Patent.

Patented Apr. 20, 1915.

Application filed May 27, 1914. Serial No. 841,313.

To all whom it may concern:

Be it known that I, CHARLES W. UNDERWOOD, a citizen of the United States, residing at Crowley, in the parish of Arcadia and State of Louisiana, have invented a new and useful Microphone, of which the following is a specification.

The present invention relates to improvements in microphones, one object of the invention, being the provision of a microphone, in which the movable agitating members of non-conducting material which produce the necessary stirring and compression upon the minute particles thereof, are disposed in the form of a blade or strip longitudinally of such particles and are carried by or attached to the vibrating member thereof, so that the most delicate sound vibration will be effective upon the particles and in which the "frying" effect is greatly minimized.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a cross section through the base and one of the present microphones mounted as a differential microphone or telephone relay. Fig. 2 is a horizontal cross sectional view through the casing of the same and at a point above the poles of the electromagnets of two watch case receivers which are used in connection with the present invention when constructed as a telephone relay. Fig. 3 is a top plan view of the casing for inclosing the differential microphone when used as a relay. Fig. 4 is a top plan view of the microphone support. Fig. 5 is a bottom plan view thereof. Fig. 6 is a plan view of the diaphragm showing the blade or strip electrodes carried thereby. Fig. 7 is an electrical diagram of the construction as illustrated in Figs. 1 and 2. Fig. 8 is a cross section through a telephone transmitter embodying the present invention. Fig. 9 is a plan view of the particle or carbon holder thereof. Fig. 10 is a bottom plan view of the closure and electrode carrying member thereof.

Referring to the drawings and more par-

ticularly to Figs. 1 through 7, the numeral 1 designates the base which has mounted thereon, a cylindrical casing 2 sealed by the cover 3 and provided with the valved nipple 4, by means of which a vacuum may be created within the same.

Disposed within the casing 2, there being two illustrated in the present structure, and as clearly shown in Fig. 2, is the base member 5 of a watch case receiver, said base having mounted therein, the usual permanent magnet 6, having the arms 7 to which are connected the pole pieces 8 of the two electromagnets 9.

The annular member 10 is screw threaded upon the casing 5 and maintains the diaphragm 12 by engaging the same at its periphery as at 11 relatively to the pole pieces 8, so that the same will be under the influence thereof. The annular member 10 is provided with the offset bridging portion 13, which is apertured as at 14, concentrically of the annular member 10 to adjustably receive the cylindrical stem 15 which is locked in adjusted relation by means of the set screw 15' to thus hold the block 16 of insulation in proper relation to the diaphragm 12. This block 16, as clearly illustrated in Figs. 1 and 5, is provided with two parallel rectangular receptacles or sockets 17—17', the socket 17 being lined at opposed sides, the said sides being the longer ones with the metal strips 18 and 19, while the socket 17' is lined with the metal strips 18' and 19', such metal strips as clearly illustrated in Fig. 5, being held in contact with or by the plates 20 and 21 of carbon, while disposed within the socket between the carbon plates is the granular material 22, preferably carbon.

Attached to the upper face of the diaphragm 12, such upper face being provided with a coat of insulation, are the two non-conducting strips or blades 23, each one of which is adapted to enter its respective socket 17 or 17' and thus contact the particles 22 and be free for vertical, and other oscillatory movements so as to agitate to produce the necessary compression of the particles during the vibration of the diaphragm 12.

Leading from the respective metal plates 19 and 19' is a conductor 24, while connected to the outer plates 18 and 18' are conductors 25 and 26, respectively, these con-

ductors being connected to the binding posts 27 and 28 which in turn are connected by conductors 29 and 30 to the binding posts 31 and 32 carried by the closure member 3 of the casing 2.

5 When the present invention is used as a telephone relay as shown in Figs. 1, 2 and 7, the cover C is disposed to cover both of the relays M and M' and the induction coils I and I', there being two of these disposed 10 and arranged as clearly shown in the diagram in Fig. 7, so that transmission may be accomplished from both directions.

In the diagram as illustrated in Fig. 7, 15 one circuit includes a source of electrical energy not shown, and at such source a transmitter and receiver, not shown, the conductors 33, 34 and the secondary coil 34' of the induction coil I being connected in 20 circuit with the electromagnets 9 of the differential relay M. The conductors 35 and 36 lead from the relay member M, and are connected to the battery 38 and the primary coil 37 of the induction coil I' and the secondary coil 38 being in the line between the conductors 39 and coils 9 of the relay M'. Thus it will be seen that the coils 9 of the relay M relay the transmission from the circuit including the conductors 33 and 34 to 25 the circuit including the conductors 39 and 40 while the coils 9 of the relay M' relay the transmission through the conductors 41, the primary coil 42 of the induction coil I, the conductor 43 and the battery 44 to the 30 transmission line including the conductors 33 and 34. By this arrangement it will be seen that the proper voice or speech transmission may be had in both directions, as the circuit including the conductors 33 and 34 is properly equipped with a transmission 35 apparatus, as well as a receiving apparatus, while the circuit including the conductors 39 and 40 is similarly equipped.

When the present microphone is employed in connection with a transmitter, the 40 same is preferably constructed and arranged as shown in Figs. 8, 9 and 10, the usual metal casing 45 being provided with the supporting apertured portion 46 and with 45 the outstanding rim 47, the metal diaphragm 48 provided with the resilient supporting rim 49 being held in place by means of the usual spring clips 50.

A strip 51 which is provided with the 50 bridging member 52 is connected diametrically to the rim 47 and socketed as at 52' for the adjustable reception of the stem 53, which is held in place by means of the screw 53'. The receptacle 54 is carried upon the 55 inner end of the stem and is lined at opposite sides with the carbon strips 55, between which are disposed the conducting granules 56 preferably of carbon. The casing 54 is opened at the end adjacent to the diaphragm 58 60 65 68 being sealed by the mica diaphragm 58

which has attached thereto, the plates 57 carrying the two non-conducting blades 23' which are similar to the blades 23 and are disposed to be projected within the granular particles 56 to agitate and compress the 70 same. The diaphragm 58 is held seated upon the casing 54 by means of the closure or fastening member 59, while the pin 60 connects the diaphragm 48 to the diaphragm 58 so that when the diaphragm 48 is vibrated due to the effect of sound waves thereupon, the most sensitive vibrations are effectual upon the particles 56, it having been found with a microphone constructed according to the present invention, that the slightest variation in sound is transmitted and effected in the major circuit so that the 80 finest articulation is possible.

From the foregoing description, it is evident that with the agitators or compression 85 members 23 and 23' disposed and arranged to coact with the particles, as shown in the two forms of microphones here illustrated, the particles are not packed and rendered more conductive as is the case where plungers 90 or buttons are used, but that the strips 23 or 23' operating within the particles produce the most sensitive and minutest compression thereof, as well as the agitation thereof, so that the slightest variation in the sound is 95 possible for transmission, giving individuality to speech and transmitting the true voice with greater accuracy.

The microphone as shown in Fig. 8 may be electrically connected to the transmitting 100 line in any desired manner, the receptacle for holding the carbon particles being an insulated member and having disposed therein, the necessary electrically conducting members so that the carbon forms the 105 transmitting means therebetween.

It will be noted that the strips 23 when used with a differential microphone, as shown in Figs. 1 and 2, are so disposed as to be in line with the poles 8 of the bi-polar 110 receiver, and therefore to be positioned to be more greatly effected thereby so that the minutest variations from the flow of current through the coils 9 will affect vibrations or movements of the strips 23. 115

What is claimed is:

1. A microphone, having a body of insulation provided with a rectangular receptacle, metal strips lining two of the opposite walls of the receptacle, a vibrating member, granular conducting material in the receptacle and bridging the metal strips, and a plurality of compressing and agitating blades disposed in parallel and actuated by the vibrating member, said blades being projected into the granular conducting material.

2. A microphone, having a support, a vibrating member mounted therein, a receptacle of non-conducting material having 130

a rectangular chamber, two metal plates lining two of the opposite walls of the chamber, granular conducting material in the chamber and bridging the two metal plates, and a compressing and agitating blade actuated by the vibrating member and disposed edgewise of and longitudinally within the chamber of the receptacle, said blade being in contact with the granular conducting material.

3. A microphone, including a support, a vibrating member, a receptacle of non-conducting material adjustably mounted in the support relatively to the vibrating member and provided with a rectangular chamber, two metal plates abutting opposite walls of the chamber, granular conducting material mounted in the chamber and bridging the metal plates, and a plurality of compressing and agitating blades disposed in parallel

and actuated by the vibrating member, said blades being projected within the receptacle into the granular conducting material.

4. A microphone, including a support, a vibrating member, a receptacle composed of non-conducting material adjustably mounted in the support, the receptacle being provided with two chambers, granular conducting material mounted in each chamber, and two blades actuated by the vibrating member and projected one within each chamber.

In testimony that I claim the foregoing as my own I have hereto affixed my signature in the presence of two witnesses.

CHARLES W. UNDERWOOD.
